UNITED STATES PATENT OFFICE.

HOWARD THURSTON, OF BEECHHURST, AND HARRY JANSEN, OF NEW YORK, N. Y.

METHOD OF AND APPARATUS FOR PRODUCING THEATRICAL ILLUSIONS.

Application filed September 9, 1925. Serial No. 55,243.

Our invention relates to a method of and apparatus for producing theatrical illusions, and more specifically considered it relates to such method and apparatus as are adapted to produce the illusion to the spectators of a plurality of persons vanishing suddenly and simultaneously.

The principal object of our invention is to provide a method of an apparatus for producing the illusion of a plurality of persons suddenly and simultaneously vanishing from the view of the spectators, portions of each person apparently being visible to the spectators until an instant before their supposed simultaneous evanishment. With the foregoing object in view, our invention contemplates the employment of apparatus whereby escape or concealment of the persons is seemingly impossible.

The nature and characteristic features of our invention will be more readily understood from the following description, taken in connection with the accompanying drawings forming part hereof, in which:—

Figure 1 is a front elevation of an apparatus embodying the main features of our invention and adapted to carry out the method thereof, the same being shown in the condition at an intermediate stage of the presentation of the illusion;

Fig. 2 is a horizontal section thereof taken approximately on the line 2—2 of Fig. 1;

Fig. 3 is a longitudinal section thereof;

Fig. 4 is a view similar to Fig. 3, but of the upper portion of the apparatus, the parts being shown in the condition at the end of the presentation;

Fig. 5 is a perspective view of the lower part of the main portion of the apparatus; and

Fig. 6 is a perspective view of one of the base pedestals upon which the main portion of the apparatus is adapted to be mounted during the presentation of the illusion.

Referring to the drawings, there is there shown a preferred form of apparatus for carrying out our invention, the same being shown mounted upon a stage 10 provided with a trap opening 11, which is adapted to be closed by a door 12 when the apparatus is not in use.

There are also provided two pedestals 13 and 14, upon which the main portion of the apparatus is adapted to be mounted during the presentation of the illusion. The pedestals 13 and 14 are alike in external appear-

ance, but the same are somewhat different as to their construction, for a purpose to be hereinafter more fully explained. The pedestal 13 comprises flat top and bottom members 15 and 16, respectively, these members 15 and 16 being connected by a central column 17, which is approximately elliptical in shape. When used, the pedestal is positioned upon the stage so that the narrowest dimension of the column 17 is presented to the view of the spectators, to thereby create the impression that the column 17 is of such relatively small size that the performers may not pass therethrough.

The column 17 of the pedestal 13 is hollow, and the top and bottom members 15 and 16 also have complementary central openings, whereby a passageway is afforded through the column 17 when the same is placed upon the stage above the trap opening 11. The top of the pedestal member 13 is closed by means of elastic webbing 18, which is made in two pieces overlapping at the center, as at 19. The top surface of the webbing 18 being preferably black, the top of the pedestal 13 will appear to be closed when the same is viewed prior to the placing of the main portion of the apparatus thereon. For the purpose of additional strength, the pedestal 13 may also be provided with strengthening rods 20, which extend at the corners between the top and bottom members 15 and 16.

The pedestal 14, as hereinbefore pointed out, is similar in external appearance to that of the pedestal 13, but this pedestal need not necessarily be of the same construction, but the flat top and bottom members 21 and 22 thereof may be solid throughout, and the central column 23 thereof will accordingly be closed at the top and bottom. The strengthening rods 24 are provided in a manner similar to that of the strengthening rods 20 of the pedestal 13.

The main portion of the apparatus comprises a framework having a base platform 25, which is preferably made as thin as possible, so that it will be obvious to the spectators that the same will not afford any means of concealment. At one end of the base platform 25 there is provided an aperture 60 extending therethrough, said aperture being preferably complementary in size and shape to the passageway afforded by the hollow column 17 of the pedestal 13. The aperture 60 is normally closed by means of

elastic webbing 61, which is preferably made in two pieces, overlapping at the center, as at 62. The top surface of the webbing 61 is preferably made black, as is also the top 5 surface of the base platform 25, so that it will appear to the spectators, when a view is afforded, that the top surface of the base platform 25 is solid throughout. In placing the main portion of the apparatus upon 10 the pedestals 13 and 14, the same is so located on said pedestals that the opening 60 will register with the passageway through the hollow column 17 of the pedestal 13.

At each end of the base platform 25 there 15 are secured a plurality of columns 26, preferably made of iron pipes. The columns 26 support, at the upper ends thereof, a canopy 27 having a central chamber 28, open at the bottom, for a purpose to be presently 20 explained. Suspended from the front of the canopy 27 is a central curtain 29, and a weight bar 30 arranged at the lower end thereof serves to cause the lower edge of the curtain to fall. The curtain 29 is adapted 25 to be raised and lowered by means of ropes 31, which extend over pulleys 32 arranged in the canopy, and thence to the exterior for manual control by one of the operators, whereby the curtain may be raised and lowered 30 during the presentation of the illusion in the manner hereinafter set forth.

At each end of the apparatus there are 35 also provided curtains 33 and 34, which preferably surround the sides, ends and rear 40 of those portions of the structure adjacent the respective sets of vertical columns 26. The curtains 33 and 34 are open on the portions thereof towards the center of the apparatus, and they are similar in arrangement, with the exception that that portion 45 of the curtain 33 which is provided at the left hand end of the apparatus has a vertical opening 35 which is normally closed by portions of the curtain overlapping each other. The curtains 33 and 34 are suitably weighted 50 by means of bars 36, bent to proper shape, and which tend normally to hold the curtains 33 and 34 down to their lowermost positions. The curtains 33 and 34 are also provided 55 with ropes 37, which extend over pulleys 38 in the canopy, and thence to the exterior for manual control by the operators for the purpose of raising and lowering said curtains when desired.

The lower ends of the columns 26 are enclosed 60 within box-like structures 40, which extend upward a short distance. These box-like structures 40 are provided for the purpose of acting as a support for a bridge member 41, one end of which is hinged, as at 65 42, to a member 43, which, in the initial condition of the apparatus, is positioned within the top of the interior of the box-like structure 40 which surrounds the lower ends of one of the inner pair of columns 26, this ar-

angement being provided so that the bridge-like structure 41 may be arranged either vertically, so as to be concealed within the curtain 33, or horizontally as shown in Figs. 1 and 3 of the drawings. The member 43 to which the bridge member 41 is hinged is mounted within the box-like support 40, so as to enable the same to be withdrawn therefrom when the bridge member 41 is elevated in the manner and for the purpose to be presently explained. 70 75

Arranged below the bridge member 41 is a board 44 having ropes 45 connected therewith, which ropes 45 extend upward over pulleys 46 in the canopy 27, and thence to the exterior for manual control by the operators. The arrangement is such that when the board 44 is elevated to the top of the structure, as shown in Fig. 4 of the drawings, the same will in its upward movement encounter the bridge member 41 and carry the same upward therewith. 80 85

There are also provided a plurality of pairs of artificial legs 47, one pair being provided for each of the performers who are to be caused to apparently vanish by means of the apparatus, and the same are provided with stockings and shoes similar to those worn by the performers. Each of the artificial legs 47 is preferably provided with a hook member 48 at the top thereof, whereby the same may be initially hung on ropes 49 secured to the columns 26 within the space enclosed by the curtain 33, being initially concealed by said curtain when so arranged. 90 95 100

The bridge member 41 is also provided with a plurality of pairs of spring clamp members 50, adapted to receive and hold the artificial leg members 47 at one stage of the presentation of the illusion, as will be hereinafter explained. 105

The central curtain 29 is provided with a plurality of apertures 51, which are covered by suitable flaps 52 (see Fig. 1), for a purpose to be presently explained. 110

The main structure, which is mounted upon the pedestals 13 and 14, is preferably provided with casters 53, for the purpose of facilitating the handling of the apparatus when it is desired to set the same up on the stage. 115

In the presentation of the illusion, the pedestals 13 and 14 are first placed upon the stage, the operators being careful that the pedestal 13 is placed over the trap opening 11 in the floor of the stage, it being understood, of course, that the door 12 of the trap is closed, and it is not apparent to the spectators that the pedestal 13 is thus placed over a stage trap. After the pedestal 13 is so placed, the door 12 of the trap may at any time thereafter be opened to afford a passageway through the trap. 120 125

The main structure is pushed upon the stage by the operators, this action being fa- 130

cilitated by the casters 53, until the same is behind the pedestals 13 and 14, whereupon the same is lifted by the operators and placed upon said pedestals, thus affording 5 a clear view beneath the apparatus, with no apparent means of escape.

When the apparatus is brought upon the stage, the side curtains 33 and 34 are preferably lowered, and the central curtain 29 is 10 preferably raised to its uppermost limit, so that a clear view is afforded to the spectators through the central part of the apparatus. The bridge member 41 is initially placed in a vertical position, and when in this position 15 is concealed by the curtain 33. The artificial leg members 47 are hung by means of the hooks 48 upon the horizontal ropes 49 within the space enclosed by the curtain 33, and are also concealed by said curtain.

20 The central curtain 29 is now lowered to the position shown in Fig. 1, whereby a clear view is afforded to the spectators of the space between the lower end of the curtain 29 and the base platform 25.

25 The performers who are to be caused to vanish, and who are preferably young women of attractive appearance, now successively enter the space enclosed by the curtain 33. The first performer to enter said 30 space quickly lowers the bridge member 41 from the vertical to the horizontal position shown in Figs. 1 and 3 of the drawings. She then takes a pair of artificial legs 47, one of said pair in each hand, and mounting 35 the bridge member 41, she places the artificial leg members down upon the board 44. She then proceeds across the bridge member 41, meanwhile manipulating the artificial leg members 47 in simulation of walking, said leg members being visible below the 40 lower edge of the central curtain 29. When the first performer to enter the structure reaches a position above the right hand end pair of spring clamp members 50, she places the pair of artificial leg members 47, which she has been manipulating, into said 45 spring clamp members with the upper portions of said leg members secured by said pair of clamp members 50, after which she 50 immediately proceeds to the space enclosed by the curtain 34, thence passing through the opening 60 in the right hand end of the base platform. She then passes downward 55 through the passageway afforded by the hollow column 17 of the pedestal 13, and thence through the trap opening 11 in the floor of the stage.

60 The other performers now separately and successively enter the space enclosed by the curtain 33, and each proceeds in like manner to take a pair of artificial leg members 47 and she manipulates the same in simulation of walking, whereby the spectators may view the same below the curtain 29, each 65 performer in turn placing her pair of artificial

leg members 47 in engagement with the respective pair of clamp members 50 provided for that purpose, and each performer, after so placing her pair of artificial leg members thereon, escapes from the apparatus by 70 means of the hollow column 17.

The last performer to enter the apparatus does not, however, immediately escape, but preferably indulges in a by-play with the principal operator or "magician", who is 75 presenting the illusion. The magician successively calling each of the performers by name, the last performer, being behind the curtain 29 upon the bridge 41, extends one of her hands successively as the various 80 names are called, through the various apertures 51, thereby serving to convince the spectators that all of the performers are still behind the curtain 29, with the lower portions of their legs, which are simulated by 85 the artificial leg members 47, in view. After this by-play, the last performer immediately makes her escape through the passageway afforded by the hollow pedestal 13, whereupon the central curtain 29 is then quickly 90 raised to its uppermost position.

The raising of the central curtain 29 is, however, preceded by the raising of the board 44 by means of the ropes 45, and as 95 said board 44 is thus elevated, the same encounters the bridge member 41 and carries the same upward also. Simultaneously, the artificial leg members 47 are carried upward and are concealed within the hollow space 28 in the canopy 27, the board 44, the bridge 100 member 41, and the lower portions of the artificial leg members 47 being concealed by the draperies, or, if desired, the central curtain 29 may be limited in its upward movement, so as to conceal the aforesaid parts 105 when said curtain is in the raised position.

Immediately after the central curtain 29 is raised, the side curtains 33 and 34 are likewise raised to their uppermost positions, whereby the spectators are afforded a clear 110 view through the apparatus, there being nothing between the base platform 25 and the canopy 27 and the elevated curtains except the relatively slender supporting columns 26. The canopy and the parts supported thereby are obviously too small for the concealment of the plurality of performers who have mysteriously vanished from the view of the spectators.

115 It will thus be seen that there is provided a novel method and apparatus whereby a plurality of performers may be caused to vanish mysteriously, portions of said performers apparently being visible to the spectators up to the time of their sudden and seemingly simultaneous evanishment. It will, of course, be understood that various modifications in the presentation, as well as in the arrangement of the apparatus, may 120 be made without departing from the spirit 125 130

of our invention, and it will also be understood that while the same is particularly adapted for the vanishing of a plurality of persons, the method and apparatus are 5 equally applicable for the vanishing of a single person if desired.

Having thus described the nature and characteristic features of our invention, what we claim as new and desire to secure by Letters Patent, is:—

1. The method of producing an illusion which consists in a performer entering a structure, said performer simulating the appearance of walking by manipulating artificial leg members in a space exposed to the view of the spectators, said performer escaping from the structure after manipulating the artificial leg members, conveying said artificial leg members to concealed locations, and finally exposing the interior of the structure to the view of the spectators.

2. The method of producing an illusion which consists in a performer entering a structure, said performer simulating the appearance first of walking and then of standing in a fixed position by manipulating artificial leg members in a space exposed to the view of the spectators, said performer escaping from the structure after manipulating the artificial leg members, conveying said artificial leg members to concealed locations, and finally exposing the interior of the structure to the view of the spectators.

3. The method of producing an illusion which consists in a performer entering a structure, said performer simulating the appearance first of walking and then of standing in a fixed position by manipulating artificial leg members in a space exposed to the view of the spectators, said performer escaping from the structure after the artificial leg members manipulated by her are placed in the fixed positions, conveying said artificial leg members to concealed locations, and finally exposing the interior of the structure to the view of the spectators.

4. The method of producing an illusion which consists in a performer entering a structure, said performer simulating the appearance first of walking and then of standing in a fixed position by manipulating artificial leg members in a space exposed to the view of the spectators, said performer escaping from the structure after the artificial leg members manipulated by her are placed in the fixed positions, then momentarily shielding the artificial leg members from the view of the spectators, then conveying said artificial leg members to concealed locations, and finally exposing the interior of the structure to the view of the spectators.

5. The method of producing an illusion which consists in a series of performers successively entering a structure, each of said

performers simulating the appearance of walking by manipulating artificial leg members in a space exposed to the view of the spectators, each performer escaping from the structure after manipulating the artificial leg members, conveying said artificial leg members to concealed locations, and finally exposing the interior of the structure to the view of the spectators.

6. The method of producing an illusion which consists in a series of performers successively entering a structure, each of said performers simulating the appearance first of walking and then of standing in fixed positions by manipulating artificial leg members in a space exposed to the view of the spectators, each performer escaping from the structure after manipulating the artificial leg members, conveying said artificial leg members to concealed locations, and finally exposing the interior of the structure to the view of the spectators.

7. The method of producing an illusion which consists in a series of performers successively entering a structure, each of said performers simulating the appearance first of walking and then of standing in fixed positions by manipulating artificial leg members in a space exposed to the view of the spectators, each performer escaping from the structure after the artificial leg members manipulated by her are placed in the fixed positions, conveying said artificial leg members to concealed locations, and finally exposing the interior of the structure to the view of the spectators.

8. The method of producing an illusion which consists in a series of performers successively entering a structure, each of said performers simulating the appearance first of walking and then of standing in fixed positions by manipulating artificial leg members in a space exposed to the view of the spectators, each performer escaping from the structure after the artificial leg members manipulated by her are placed in the fixed positions, then momentarily shielding the artificial leg members from the view of the spectators, then conveying said artificial leg members to concealed locations, and finally exposing the interior of the structure to the view of the spectators.

9. The method of producing an illusion which consists in a series of performers successively entering a structure, each of said performers simulating the appearance first of walking and then of standing in fixed positions by manipulating artificial leg members in a space exposed to the view of the spectators, each performer escaping from the structure after the artificial leg members manipulated by her are placed in the fixed positions, one of said performers immediately before her escape exposing her hand successively from a plurality of locations to

create the impression thereby that all of the performers are still within the structure, then momentarily shielding the artificial leg members from the view of the spectators, 5 then conveying said artificial leg members to concealed locations, and finally exposing the interior of the structure to the view of the spectators.

10. In apparatus of the character described, means for the concealed passage of performers across a portion of the structure, and artificial leg members made in simulation of the legs of the performers and adapted to be manipulated by the performers in 15 simulation of walking in a space exposed to the view of the spectators.

11. In apparatus of the character described, means for the concealed passage of performers across a portion of the structure, 20 artificial leg members made in simulation of the legs of the performers and adapted to be manipulated by the performers in simulation of walking in a space exposed to the view of the spectators, means for holding 25 said artificial leg members in fixed positions, and means for moving said artificial leg members to concealed locations.

12. In apparatus of the character described, a structure having a platform, 30 means for the concealed passage of performers across a portion of the structure, artificial leg members made in simulation of the legs of the performers and adapted to be manipulated by the performers in simulation 35 of walking across the platform, and means adapted to conceal the space in a portion of the structure and to arbitrarily expose the same fully or partially to the view of the spectators when desired.

40 13. In apparatus of the character described, a structure having a platform, means for the concealed passage of performers across a portion of the structure, artificial leg members made in simulation 45 of the legs of the performers and adapted to be manipulated by the performers in simulation of walking across the platform, means for holding said artificial leg members in fixed positions, means for moving said artificial leg members to concealed locations, and means adapted to conceal the space in 50 a portion of the structure and to arbitrarily expose the same fully or partially to the view of the spectators when desired.

55 14. In apparatus of the character described, a structure having a platform, means for the concealed passage of performers across the central portion of the structure, artificial leg members made in simulation 60 of the legs of the performers and adapted to be manipulated by the performers in simulation of walking across the platform, means for raising the artificial leg members to concealed locations, means adapted to conceal the space at the end portions of the 65

structure and to arbitrarily expose the same to the view of the spectators when desired, and means adapted to conceal the space in the central portion of the structure and to arbitrarily expose the same fully or partially to the view of the spectators when desired. 70

15. In apparatus of the character described, a structure having a platform, means for the concealed passage of performers across the central portion of the structure, artificial leg members made in simulation of the legs of the performers and adapted to be manipulated by the performers in simulation of walking across the platform, 80 means for holding said artificial leg members in fixed positions, means for raising said artificial leg members to concealed locations, means adapted to conceal the space at the end portions of the structure and to arbitrarily expose the same to the view of the spectators when desired, and means adapted to conceal the space in the central portion of the structure and to arbitrarily expose the same fully or partially to the view of the spectators when desired. 85

16. In apparatus of the character described, a structure having a platform, a bridge member affording means for the concealed passage of performers across the central portion of the structure, means for supporting said bridge member above the platform, means for raising said bridge member to a concealed location, means adapted to conceal the space at the end portions of the structure and to arbitrarily expose the same to the view of the spectators when desired, and means adapted to conceal the space in the central portion of the structure and to arbitrarily expose the same fully or partially to the view of the spectators when desired. 95

17. In apparatus of the character described, a structure having a platform, a bridge member affording means for the concealed passage of performers across the central portion of the structure, means for supporting said bridge member above the platform, artificial leg members made in simulation of the legs of the performers and adapted to be manipulated by the performers in the space below the bridge member in simulation of walking, means adapted to conceal the space at the end portions of the structure and to arbitrarily expose the same to the view of the spectators when desired, and means adapted to conceal the space in the central portion of the structure and to arbitrarily expose the same fully or partially to the view of the spectators when desired. 110

18. In apparatus of the character described, a structure having a platform, a bridge member affording means for the concealed passage of performers across the central portion of the structure, means for supporting said bridge member above the plat- 125

form, artificial leg members made in simulation of the legs of the performers and adapted to be manipulated by the performers in the space below the bridge member 5 in simulation of walking, means for raising said bridge member and the artificial leg members to concealed locations, means adapted to conceal the space at the end portions of the structure and to arbitrarily expose the same to the view of the spectators when desired, and means adapted to conceal the space in the central portion of the structure and to arbitrarily expose the same fully or partially to the view of the spectators 10 when desired.

19. In apparatus of the character described, a structure having a platform, a bridge member affording means for the concealed passage of performers across the central portion of the structure, means for supporting said bridge member above the platform, artificial leg members made in simulation of the legs of the performers and adapted to be manipulated by the performers in the space below the bridge member 15 in simulation of walking, means for holding said artificial leg members in fixed positions, means for raising said bridge member and the artificial leg members to concealed locations, means adapted to conceal the space at the end portions of the structure and to arbitrarily expose the same to the view of the spectators when desired, and means adapted to conceal the space in the central portion of the structure and to arbitrarily expose the same fully or partially to the view of the spectators when desired. 20

20. In apparatus of the character described, a structure having a platform, a canopy, and relatively slender columns supporting said canopy above the platform, a bridge member affording means for the concealed passage of performers across the central portion of the structure, means for supporting said bridge member above the platform, artificial leg members made in simulation of the legs of the performers and adapted to be manipulated by the performers in the space below the bridge member 25 in simulation of walking, means for holding said artificial leg members in fixed positions, means for raising said bridge member and the artificial leg members to the canopy, the canopy having a chamber adapted to receive said artificial leg members when the same are raised, means adapted to conceal the space at the end portions of the structure and to arbitrarily expose the same to the view of the spectators when desired, and means adapted to conceal the space in the central portion of the structure and to arbitrarily expose the same fully or partially to the view of the spectators when desired. 30

21. In apparatus of the character de-

scribed, a structure having a platform, a canopy, and relatively slender columns supporting said canopy above the platform, a bridge member affording means for the concealed passage of performers across the central portion of the structure, means for supporting said bridge member above the platform, artificial leg members made in simulation of the legs of the performers and adapted to be manipulated by the performers in the space below the bridge member 35 in simulation of walking, means for holding said artificial leg members in fixed positions, means for raising said bridge member and the artificial leg members to the canopy, the canopy having a chamber adapted to receive said artificial leg members when the same are raised, means adapted to conceal the space at the end portions of the structure and to arbitrarily expose the same to the view of the spectators when desired, means adapted to conceal the space in the central portion of the structure and to arbitrarily expose the same fully or partially to the view of the spectators when desired, and means for supporting said structure above a theatre stage, said supporting means having a concealed escape passageway and the platform of said structure having a concealed opening adapted to register with the passageway in the supporting means. 40

22. In apparatus of the character described, a frame work comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, and means for the concealed passage of the performers across the space between the end curtains when the central curtain is partially lowered. 45

23. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, means for the concealed passage of the performers across the space between the end curtains when the central curtain is partially lowered, and artificial leg members made in simulation of the legs of the performers and adapted to be manip- 50

ulated by the performers in simulation of walking.

24. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, means for the concealed passage of the performers across the space between the end curtains, artificial leg members made in simulation of the legs of the performers and adapted to be manipulated by the performers in simulation of walking, means for holding said artificial leg members in fixed positions, and means for raising the artificial leg members to concealed locations.

25. 25. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, means for the concealed passage of the performers across the space between the end curtains, artificial leg members made in simulation of the legs of the performers and adapted to be manipulated by the performers in simulation of walking, means for holding said artificial leg members in fixed positions, a board initially positioned on the top of the base platform, means for raising said board thereby to carry the artificial leg members up to the canopy, the canopy having a chamber adapted to receive said artificial leg members when the board is raised.

26. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, a bridge member adapted to be arranged across the space between the end curtains, and means for supporting said bridge member above the base platform, the central curtain

being adapted when partially lowered to conceal said bridge member when the same is so arranged, and the bridge member affording means for the concealed passage of the performers across the space between the end curtains.

27. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, a bridge member adapted to be arranged across the space between the end curtains, means for initially concealing said bridge member, and means for supporting said bridge member above the base platform, the central curtain being adapted when partially lowered to conceal said bridge member when the same is so arranged, and the bridge member affording means for the concealed passage of the performers across the space between the end curtains.

28. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, a bridge member adapted to be initially concealed by one of the end curtains and adapted to be arranged across the space between the end curtains, and means for supporting said bridge member above the base platform, the central curtain being adapted when partially lowered to conceal said bridge member when the same is so arranged, and the bridge member affording means for the concealed passage of the performers across the space between the end curtains.

29. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, a bridge mem-

ber adapted to be initially concealed by one of the end curtains and adapted to be arranged across the space between the end curtains, means for supporting said bridge member above the base platform, the central curtain being adapted when partially lowered to conceal said bridge member when the same is so arranged, and the bridge member affording means for the concealed passage of the performers across the space between the end curtains, and artificial leg members made in simulation of the legs of the performers and adapted to be manipulated by the performers in the space below the bridge member in simulation of walking.

30. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, a bridge member adapted to be initially concealed by one of the end curtains and adapted to be arranged across the space between the end curtains, means for supporting said bridge member above the base platform, the central curtain being adapted when partially lowered to conceal said bridge member when the same is so arranged, and the bridge member affording means for the concealed passage of the performers across the space between the end curtains, artificial leg members made in simulation of the legs of the performers and adapted to be manipulated by the performers in the space below the bridge member in simulation of walking, and means carried by the bridge member for holding said artificial leg members in fixed positions.

45. 31. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, a bridge member adapted to be initially concealed by one of the end curtains and adapted to be arranged across the space between the end curtains, means for supporting said bridge member above the base platform, the central curtain being adapted when partially lowered to conceal said bridge member when the same is so arranged, and the bridge member affording means for the concealed passage of

the performers across the space between the end curtains, artificial leg members made in simulation of the legs of the performers and adapted to be manipulated by the performers in the space below the bridge member in simulation of walking, means carried by the bridge member for holding said artificial leg members in fixed positions, and means for raising said bridge member and artificial leg members.

32. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, a bridge member adapted to be initially concealed by one of the end curtains and adapted to be arranged across the space between the end curtains, means for supporting said bridge member above the base platform, the central curtain being adapted when partially lowered to conceal said bridge member when the same is so arranged, and the bridge member affording means for the concealed passage of the performers across the space between the end curtains, artificial leg members made in simulation of the legs of the performers and adapted to be manipulated by the performers in the space below the bridge member in simulation of walking, means carried by the bridge member for holding said artificial leg members in fixed positions, and means for raising said bridge member and the artificial leg members to the canopy, the canopy having a chamber adapted to receive said artificial leg members when the same are raised.

33. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, a bridge member adapted to be initially concealed by one of the end curtains and adapted to be arranged across the space between the end curtains, means for supporting said bridge member above the base platform, the central curtain being adapted when partially lowered to conceal said bridge member when the same is so arranged, and the bridge member affording

means for the concealed passage of the performers across the space between the end curtains, artificial leg members made in simulation of the legs of the performers and adapted to be manipulated by the performers in the space below the bridge member in simulation of walking, means carried by the bridge member for holding said artificial leg members in fixed positions, a board initially positioned on the top of the base platform, and means for raising said board thereby to carry the bridge member and the artificial leg members upward.

34. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, a bridge member adapted to be initially concealed by one of the end curtains and adapted to be arranged across the space between the end curtains, means for supporting said bridge member above the base platform, the central curtain being adapted when partially lowered to conceal said bridge member when the same is so arranged, and the bridge member affording means for the concealed passage of the performers across the space between the end curtains, artificial leg members made in simulation of the legs of the performers and adapted to be manipulated by the performers in the space below the bridge member in simulation of walking, means carried by the bridge member for holding said artificial leg members in fixed positions, a board initially positioned on the top of the base platform, and means for raising said board thereby to carry the bridge member and the artificial leg members up to the canopy, the

canopy having a chamber adapted to receive said artificial leg members when the board is raised.

35. In apparatus of the character described, a framework comprising a base platform, a canopy, and relatively slender columns supporting said canopy above the base platform, curtains suspended from the canopy adapted to partially enclose the end portions of the framework, means for raising and lowering said curtains, a central curtain suspended from said canopy extending across the front of the framework between the curtains at the end portions thereof, means for raising and lowering said central curtain, a bridge member adapted to be initially concealed by one of the end curtains and adapted to be arranged across the space between the end curtains, means for supporting said bridge member above the base platform, the central curtain being adapted when partially lowered to conceal said bridge member when the same is so arranged, and the bridge member affording means for the concealed passage of the performers across the space between the end curtains, artificial leg members made in simulation of the legs of the performers and adapted to be manipulated by the performers in the space below the bridge member in simulation of walking, means carried by the bridge member for holding said artificial leg members in fixed positions, a board initially positioned on the top of the base platform, means for raising said board thereby to carry the bridge member and the artificial leg members up to the canopy, the canopy having a chamber adapted to receive said artificial leg members when the board is raised, and means for supporting the framework above a theatre stage, said supporting means having a concealed escape passageway.

In testimony whereof, we have hereunto signed our names.

HOWARD THURSTON.
HARRY JANSEN.
